FLEXIBLE COMBINED CONTROL WIRE FOR REMOTE FORCE TRANSMISSION AND PLASTIC COVERED HOUSING THEREFOR OR SIMILAR ARTICLE

Alvin A. Cadwallader, Hatboro, Pa., assignor to Teleflex Incorporated, North Wales, Pa., a corporation of Delaware

Filed Nov. 20, 1961, Ser. No. 67,612

Term of patent 14 years

(Cl. D14—3)

Fig. 1

Fig. 2

Fig. 3

Fig. 4

FIG. 1 is an end, top and side perspective view of a flexible combined control wire for remote force transmission and plastic covered housing therefor or similar article, showing my new design;

FIG. 2 is a bottom plan view;

FIG. 3 is an opposite side elevational view; and

FIG. 4 is an opposite end elevational view thereof.

The subject design comprises a flexible strip, e.g., metal, having alternately offset tunnel portions. The strip is covered with a thin layer of plastic material which reveals the outline of the tunnel portions. A wire core member is movably disposed within the tunnel portions of the covered strip.

I claim:

The ornamental design for a flexible combined control wire for remote force transmission and plastic covered housing therefor or similar article, substantially as shown and described.
